V. C. DE YBARRONDO

FILM DEVELOPING MACHINE HAVING POSITIVE DRIVE

Filed Aug. 9, 1926

INVENTOR:
VINCENT C. DE YBARRONDO,
By *Floyd D. Harris*

ATTORNEY.

UNITED STATES PATENT OFFICE.

VINCENT C. DE YBARRONDO, OF LOS ANGELES, CALIFORNIA.

FILM-DEVELOPING MACHINE HAVING POSITIVE DRIVE.

Application filed August 9, 1926. Serial No. 128,039.

This invention relates to the art of developing photographic film, and it is embodied in an automatic film developing machine especially suited for developing motion picture film. In this art both positive and negative film, after their exposure, are subjected to a series of treatments which prepare them for the cutting room. The exposed film generally passes through the following steps. 5 The film is first developed by immersion in a developing solution; the images are fixed thereon by immersion of the film in a fixative solution; the film is then cleansed of all the adhering solutions by immersion in a wash; 10 the film may then be dyed and toned as desired; and the film is then dried. The film thus treated is ready for the cutting room. Motion picture films are carried through this series of treatments either manually or 15 by automatic apparatus and my invention relates to an automatic apparatus for carrying a motion picture film through the series of treatments enumerated above. In such machines the film is passed through the various 20 solution tanks or "wet box" and the drying compartments or "dry box". The wet box and the dry box have series of upper and lower spools or rollers on which the film is wound. In the usual film developing machine 25 the drive rollers thereof are driven through a friction means, such as a friction clutch, from a drive shaft which operates at a constant rate of speed. The lower rollers are rotatably disposed on a fixed shaft. 30 When the tension of the film passing through such a machine is greater than normal tension, the friction will slip until the film is returned to normal tension. It is evident 35 that the maintaining of the film at a uniform and normal tension is somewhat precarious since the operation of such a friction clutch is not altogether certain.

I have discovered that the tension of the film may be accurately controlled by positively driving the upper rollers at a uniform 40 rate of speed and by floating the lower rollers; that is, arranging the lower rollers so that they may move vertically and so that they are supported entirely by the film which 45 passes therearound.

It is accordingly one of the objects of this invention to provide a film developing apparatus in which the upper rollers are positively driven at a substantially uniform rate 50 of speed and in which the lower rollers are

full-floating and are supported entirely by the film.

The film developing apparatus is generally divided into a number of units, each of which is operated by a separate drive means. 60 The wet box may be divided into a series of units and the dry box may also be divided into a series of units, each of the different units having a separate drive means. It often occurs that the different units will not 65 be operated at the same rate of speed and one of them will operate faster or slower than the other of the units, this causing either a slack or a tension in the film which is detrimental to the film. 71

It is an object of this invention to provide a film developing apparatus in which the operation of one of the units is controlled so that it will operate in congruency with the other of the units. 75

In order to accomplish the last named object of the invention it has been necessary to devise a special form of rheostat operated entirely by the film passing through the developing apparatus. 80

It is another object of my invention to provide a novel film operated rheostat.

Other objects and advantages will be made manifest hereinafter.

Referring to the drawings, which are 85 solely for the purpose of illustration and in which I illustrate a preferred form of the invention:

Fig. 1 is an elevational view partially sectioned of the invention. 90

Fig. 2 is a fragmentary plan view taken on the line 2-2 of Fig. 1.

Fig. 3 is a section taken on the line 3-3 of Fig. 1.

Fig. 4 is an enlarged fragmentary view of 95 the novel rheostat of my invention.

Referring in detail to the drawings, particularly Fig. 1, the numeral 11 represents primary and secondary units which in the drawings are shown as identical and being 100 part of the wet box of the film developing apparatus. It should be clearly understood that these units 11 may be dissimilar and one or both may be a part of the dry box. Since each of the units as shown are identical, only 105 the left-hand or primary unit will be described in detail.

Referring to this unit, 12 represents a tank in which a suitable solution or solutions may be placed. Supported at the upper part of 110

the tank 12 is a frame 13 having side bars 14 and end bars 15. Extending across the frame 13 and rotatably supported by the side bars 14 are drive shafts 16. Rigidly secured to the drive shafts 16 are upper drive rollers 17 around which a film 18, which is being treated, is passed. Rigidly secured on the outer ends of the drive shafts 16 are drive gears 19, between which are intermediate gears 20. The intermediate gears 20 are rotatably supported by brackets 21 and are in mesh with adjacent drive gears 19. The drive gears and intermediate gears 19 and 20 are driven by means of a motor 22 having a gear 23 which engages and operates one of the drive gears 19, the other gears being driven therefrom. The motor 22 is connected in an electric circuit 24. A control device 25 is provided for controlling the supply of current to the motor 22 of the primary unit.

Extending downward into the tank 12 from the side bars 14 of the frame 13 are vertical legs 28. The vertical legs 28 are provided with vertical slots 30. Extending between the bars of vertical legs 28 are floating shafts 31 having heads 32 which rest in the vertical slots 30. The floating shafts 32 are free to move vertically in the slots 30 but are restrained from horizontal or lateral movement. Supported on the floating shafts 31 are full floating lower rollers 33. The film passes around the under sides of the floating rollers 33 and supports them as illustrated in Fig. 1.

33 The film, in passing from the left-hand or primary unit 11 to the right-hand or secondary unit, passes over a roller 35 and over a second roller 36, there being a loop 37 formed therebetween. Supported at the lower end of the loop 37 is a pulley 38 which is attached by a connection 39 to the outer end of an arm 40. The arm 40 is extended from a contact drum 41 of the automatic rheostat of my invention. The contact drum 41 is pivotally supported on a shaft 42, which shaft 42 is in turn carried by a frame 43. The rheostat contact drum 41 is provided with a series of contacts 44 which are consecutively connected together by resistance wires 45. One of the end contacts 44 is connected to a wire 46 which forms a part of the circuit 24. The automatic rheostat of the invention also includes a contact finger 47 which is adapted to engage one of the contacts 44 according to the position of the drum 41. The contact finger 47 is connected to a wire 49 which forms a part of the circuit 24 and which is connected to one of the terminals of the motor 22 which operates the right-hand unit 11.

The control device or rheostat 25, which operates the left-hand unit 11, is manually operated and may be set so that the left-hand unit will operate at any desired rate of speed. The right-hand unit 11 is controlled in speed

by the automatic rheostat which is actuated by the loop 37 of the film 18.

The complete operation of the invention is as follows:

The film is first wound around the drive and floating rollers 17 and 33, as illustrated in the drawings. The floating rollers 33 are full floating and are entirely supported by the loops of the film 18. After the film (or a leader) has been wound as shown in Fig. 1, the circuit 24 may be completed and both of the motors 22 set into operation. The drive rollers 17 are each driven positively and at a uniform rate of speed. The weight of the floating rollers 33 maintains the tension of the film uniformly at a normal tension. In case of any variations in the lengths of the loops which support the floating rollers 33, the floating rollers may move up or down, this being permitted by the heads of the floating shafts 31 which may move up or down in the slots 30.

In the event that the first unit operates at a faster rate of speed than the second unit or that the film stretches, the loop 37 which supports the pulley 38 will lengthen and the contact drum 41 will rotate in a direction indicated by the arrow 50 of Figs. 1 and 4. If necessary, a weight (Fig. 1) may be attached to the arm 40. When the contact drum 41 is rotated, a different contact 44 is moved into engagement with the contact finger 47, and some resistance is cut out of that portion of the circuit 24, which is connected to the secondary motor 22, which operates the secondary or right-hand unit 11. Therefore, the motor of the right-hand unit will be accelerated in speed and the loop 37 will be shortened to a normal length, at which time the contact drum will be rotated to normal position. If the left-hand unit 11 runs slower than the right-hand unit 11, the loop 37 will shorten and more resistance will be inserted in that portion of the circuit 24 which extends to the motor 22 of the right-hand unit 11, so that the speed thereof will be slowed up, this resulting in the lengthening of the loop 37.

It is often necessary to speed up or slow down the operation of the film developing apparatus according to the exposure of the film. This may be accomplished in the invention by operating the rheostat 25. This speeds up the operation of the left-hand unit 11, and the automatic rheostat of the invention will automatically speed up the operation of the right-hand unit 11, in agreement with the left-hand unit 11.

The invention, as fully disclosed, is of simplified construction and positive in operation. The tension of the film will be maintained at normal and requires no adjustment and will give no trouble. One of the important parts of the invention, as has been emphasized heretofore, is the positive driv-

ing of the drive roller 17 and the full floating feature of the floating rollers 33. Another important feature of the invention is the controlling of one of the units so that it operates in agreement with the other of the units. Another feature of the invention resides, as previously pointed out, in the novel rheostat, which is very important.

I claim as my invention:

- 10 1. A film developing apparatus comprising: a primary unit having drive rollers, there being a film handled by said primary unit; a secondary unit having drive rollers, said film being also handled by said secondary unit; a primary motor for operating said drive rollers of said primary unit; a secondary drive motor for operating the drive rollers of said secondary unit; a contact drum connected in a circuit to said secondary motor, said contact drum having a plurality of contacts in series; a pulley attached to said contact drum, said film supporting said pulley and thus determining the position of said contact drum; and a contact finger connected in the circuit of said secondary motor, said contact finger engaging one of said contacts according to the position of said contact drum, said contact drum and said contact finger supplying current to said secondary motor so that said secondary unit will operate in congruency with said primary unit. 55
- 15 2. A film developing apparatus comprising: a primary unit having drive rollers, there being a film handled by said primary unit; a secondary unit having drive rollers, said film being also handled by said secondary unit; a primary motor for operating said drive rollers of said primary unit; a secondary drive motor for operating the drive rollers of said secondary unit; means for controlling the supply of current to said primary motor; a contact drum connected in a circuit to said secondary motor, said 60 contact drum having a plurality of contacts in series; a pulley attached to said contact drum, said film supporting said pulley and thus determining the position of said contact drum; and a contact finger connected in the circuit of said secondary motor, said contact finger engaging one of said contacts according to the position of said contact drum, said contact drum and said contact finger supplying current to said secondary motor so that said secondary unit will operate in congruency with said primary unit. 65
- 20 3. A film developing apparatus comprising: a frame; a plurality of drive shafts journaled in spaced relation on said frame so as to be substantially parallel and on the same level; drive rollers, one of which is rigidly fixed upon each of said shafts; means for driving said shafts positively and in synchronism; substantially vertical struts provided on said frame, a pair of said struts being disposed under the space between each adjacent pair of shafts, the struts of each of said pairs being provided with co-operating, substantially vertical guideways; travelling shafts, each of which has end formations adapted to slide within said guideways of one of said pairs of struts; travelling pulleys, one of which is rotatably mounted upon each of said travelling shafts; and a leader ribbon which is adapted to be threaded through said apparatus so as to alternately pass over the top of one of said drive pulleys and under the next succeeding one of said travelling pulleys so as to support said travelling pulleys so that any stretch or shrinkage in any portion of a film drawn into said apparatus by said leader ribbon is compensated for by the falling or rising of the travelling pulley supported by said portion of film. 70
- 25 4. A film developing apparatus comprising: a primary unit having drive rollers, there being a film handled by said primary unit; a secondary unit having drive rollers, said film being also handled by said secondary unit; a primary motor for operating said drive rollers of said primary unit; a secondary drive motor for operating the drive rollers of said secondary unit; means for controlling the supply of current to said primary motor; a contact drum connected in a circuit to said secondary motor, said 75 contact drum having a plurality of contacts in series; a pulley attached to said contact drum, said film supporting said pulley and thus determining the position of said contact drum; and a contact finger connected in the circuit of said secondary motor, said contact finger engaging one of said contacts according to the position of said contact drum, said contact drum and said contact finger supplying current to said secondary motor so that said secondary unit will operate in congruency with said primary unit. 80
- 30 5. A film developing apparatus comprising: a primary unit having drive rollers, there being a film handled by said primary unit; a secondary unit having drive rollers, said film being also handled by said secondary unit; a primary motor for operating said drive rollers of said primary unit; a secondary drive motor for operating the drive rollers of said secondary unit; means for controlling the supply of current to said primary motor; a contact drum connected in a circuit to said secondary motor, said 85 contact drum having a plurality of contacts in series; a pulley attached to said contact drum, said film supporting said pulley and thus determining the position of said contact drum; and a contact finger connected in the circuit of said secondary motor, said contact finger engaging one of said contacts according to the position of said contact drum, said contact drum and said contact finger supplying current to said secondary motor so that said secondary unit will operate in congruency with said primary unit. 90

In testimony whereof, I have hereunto set my hand at Los Angeles, California, this 3rd day of August, 1926.

VINCENT C. DE YBARRONDO.
